[57] CLAIM

The ornamental design for an island vending machine, as shown and described.

DESCRIPTION

FIG. 1 is a top front and right side perspective view of an island vending machine, showing out new design; FIG. 2 is a top rear left side perspective view thereof; FIG. 3 is a top plan view thereof; FIG. 4 is a end elevational view thereof; FIG. 5 is a top front and right side perspective view of a second embodiment of that shown in FIG. 1, the rear perspective view being an identical image thereof; FIG. 6 is a top front and right side perspective view of a third embodiment of that shown in FIG. 1, the rear perspective view being an identical image thereof; FIG. 7 is a top front and right side perspective view of a fourth embodiment of that shown in FIG. 1, the rear perspective view being an identical image thereof; and FIG. 8 is a top plan view thereof.

The end elevational views of embodiments 2-4 are substantially the same as that shown in FIG. 4. The top plan views of embodiments 2 and 3 are the same as that shown in FIG. 3.

The broken lines indicating indicia in FIGS. 1-2 and 5-7 are shown for illustrative purposes only.

FIG. 1

FIG. 2

FIG. 3

FIG. 4

FIG. 5

FIG. 6

FIG. 7

FIG. 8
